(57) **CLAIM**

The ornamental design for an electric bicycle frame as shown and described.

DESCRIPTION

1. Electric bicycle frame

1.1 is a top, rear and right-side perspective view of an electric bicycle frame embodying our new design;

1.2 is a front elevation view thereof;

1.3 is a rear elevation view thereof;

1.4 is a right-side elevation view thereof;

1.5 is a left-side elevation view thereof;

1.6 is a top plan view thereof; and

1.7 is a bottom plan view thereof.

The broken lines shown in the figures are for the purpose of illustrating portions of the electric bicycle frame and form no part of the claimed design.

1 Claim, 7 Drawing Sheets
